Filed May 6, 1970, Ser. No. 22,845

Term of patent 14 years

Int. Cl. D11—04

U.S. Cl. D29—1

FIG. 1

FIG. 1 is a front elevational view of a Christmas ornament showing my new design;

FIG. 2 is a side elevational view thereof, the side opposite being a mirror image thereof; and

FIG. 3 is a second embodiment of the design shown in FIG. 1.

The characteristic feature of my design for a Christmas ornament resides in the combination of a cone body and a nut head having a peaked hat, all as shown by the drawing.

I claim:

The ornamental design for a Christmas ornament, as shown and described.
